(57) **CLAIM**

The ornamental design for a herb flower grinder including flip handle, as shown and described.

DESCRIPTION

FIG. 1 is a perspective view of an herb flower grinder including a flip handle of my new design with the flip handle in a first position;

FIG. 2 is a front elevation view of the herb flower grinder of my new design with the flip handle in the first position; FIG. 3 is a rear elevation view of the herb flower grinder of my new design with the flip handle in the first position; FIG. 4 is a side elevation view of the herb flower grinder of my new design with the flip handle in the first position; FIG. 5 is an opposite side elevation view of the herb flower grinder of my new design with the flip handle in the first position;

FIG. 6 is a top plan view of the herb flower grinder of my new design with the flip handle in the first position; FIG. 7 is a bottom plan view of the herb flower grinder of my new design with the flip handle in the first position; FIG. 8 is a perspective view of the herb flower grinder including a flip handle of my new design with the flip handle in a second position;

FIG. 9 is a front elevation view of the herb flower grinder of my new design with the flip handle in the second position; FIG. 10 is a rear elevation view of the herb flower grinder of my new design with the flip handle in the second position; FIG. 11 is a side elevation view of the herb flower grinder of my new design with the flip handle in the second position; FIG. 12 is an opposite side elevation view of the herb flower grinder of my new design with the flip handle in the second position;

FIG. 13 is a top plan view of the herb flower grinder of my new design with the flip handle in the second position; and, FIG. 14 is a bottom plan view of the herb flower grinder of my new design with the flip handle in the second position. Any broken-line illustration in the drawing disclosure is not a part of the design sought to be patented. Similarly, lines indicating shading are included for illustrative purposes to better perceive the three-dimensional structure of the claimed design but are not otherwise meant to be limiting in any manner.
